UNITED STATES PATENT OFFICE.

ALFRED L. SOHM, OF CHICAGO, ILLINOIS.

KEYLESS CLOCK.

1,418,487.

Specification of Letters Patent. Patented June 6, 1922.

Application filed September 18, 1919. Serial No. 324,535.

To all whom it may concern:

Be it known that I, ALFRED L. SOHM, a citizen of the United States, and a resident of Chicago, in the county of Cook and State 5 of Illinois, have invented certain new and useful Improvements in Keyless Clocks, of which the following is a specification.

My invention relates to keyless clocks and particularly to electrically wound clocks and 10 covers several new features of construction, arrangement and operation.

In electrically self-winding clocks electro-magnet mechanism is provided and its circuit periodically closed by contacts operated 15 by the clock mechanism, the electro-magnet mechanism operating the wind-up mechanism. I have found that in order to guarantee efficient operation of a clock during a long period of time, the contacts governing 20 the electro-magnet circuit must be kept scrupulously clean. One of the important objects of my invention is therefore to provide efficient means for thoroughly cleaning the contacts before they come into engagement. In 25 accordance with my invention, not only is every contact cleaned but each contact is cleaned several times before engagement, and furthermore the contact cleaning members are themselves cleaned before they enter into 30 engagement with a contact for the purpose of cleaning. Such arrangement insures bright and clean contact surfaces.

In clocks of the class referred to a contact lever forms one terminal of the electric 35 circuit and a contact wheel driven by the clock work and having contact projections forms the other terminal of the circuit, and provision is usually made to disconnect or kick off the lever from the contact wheel as 40 soon as contact is made, such kick off being usually controlled by the electro-magnet. Another important object of my invention is to provide improved kick off mechanism in the form of lever mechanism adapted to be 45 powerfully actuated by the electro-magnet armature and having sufficient travel to assure full disconnection of the contact lever from the contact wheel. The above arrangement permits only instantaneous contact engagement of the contact lever and 50 wheel, and this together with the clean, smooth contact surfaces reduces the friction or resistance to the clock movements to a minimum. This enables me to use a small 55 finely tempered steel main spring, and a small, light spring requires less electro-mag-

net force for re-winding and consequently less current. Where batteries are used, their life is thus greatly increased.

The above and other features of my invention are disclosed in detail in the accompanying specification taken with the accompanying drawings, in which drawings

Fig. 1 is a side elevational view of clock mechanism,

Fig. 2 is a front elevational view from plane 2—2, Fig. 1,

Fig. 3 is a sectional view on plane 3—3, Fig. 1,

Fig. 4 is a diagrammatic view showing the electrical circuit, and

Figs. 5, 6, 7 and 8 show progressive positions of the contact members and cleaning mechanism.

The supporting frame for the operating 75 mechanism comprises the base 10, the front and rear plates 11 and 12 and the upper spacing members 13. Journaled in the front and rear plates is the minute arbor 14 for supporting the minute hand 15, the hub 16 80 supporting the hour hand 17 being connected through a train of gears 18 with the minute arbor. On the arbor 14 is secured the gear 19 which meshes with the pinion 20 on the center arbor 21. On this arbor is secured the gear 22 which meshes with the pinion 23 on the escapement arbor 24 which carries the escapement wheel 25 engaged by the escapement beam 26 supported on the upper arbor 27. A lug 28 extending rear- 90 wardly from the plate 12 supports the spring link 29 on which is hung the pendulum rod 30 carrying at its lower end the pendulum weight 30', the actuating rod 31 being secured to the arbor 27 and connecting at its lower end with the pendulum in the well known manner.

Secured to the minute arbor 14 adjacent the gear 19 is the barrel 32 containing the main spring 33, one end of this spring being 100 secured to the barrel and the other being secured to the ratchet frame 34 rotatable on the arbor adjacent the spring barrel. The ratchet frame has the ratchet teeth 35 engaged at the opposite sides of the frame by 105 a push-pawl lever 36 and a pull-pawl lever 37 respectively. The pawls are pivoted to a plate 38 at their lower ends, the plate being connected at its lower end with the armature 39 which is hinged at its front to the 110 base 10. The vertical movement of the plate is guided by means of the slot 40 which

receives the grooved collar 41 secured to the minute arbor. Springs 42 and 43 connecting between the pawl levers and the plate tend to hold the pawl points in engagement with the ratchet teeth. The electro-magnet frame 44 is supported below the base 10 with its pole ends projecting through the base below armature 39. The energizing windings *w* mounted on the electro-magnet frame are connected in circuit in a manner be described later. When the electro-magnet frame is energized the armature will be drawn downwardly toward the pole ends, and the plate 38 will be drawn downwardly with the armature, the pull-pawl 37 rotationally advancing the ratchet frame 35. A tension spring 45 connecting between the armature and the frame plate 12 will swing the armature upwardly when the electro-magnet frame is to be energized, and such upward movement of the armature will shift the plate 30 upwardly and cause the push-pawl 36 to advance the ratchet frame. Such advancements of the ratchet frame cause incremental winding up of the main spring and storage of spring energy for operating the clock.

Contact mechanism, controlled by the clock, is provided for periodically closing the energizing circuit, the timing being such that the main spring will be kept sufficiently wound up at all times to operate the clock mechanism. The contact mechanism shown comprises a contact wheel 46 and a contact lever 47, the contact lever being pivoted on the frame by means of the arbor 48. The lever is adapted to swing in the plane of the contact wheel and carries the contact 49 insulated therefrom by insulation 50, this contact engaging successively with the contact projections or teeth *a*, *b*, *c*, and *d* of the contact wheel. In the arrangement shown these contact teeth are spaced so that contact will be made every two minutes. Any other timing could however be arranged for depending upon the frequency of the winding increments necessary for maintaining proper and efficient operation of the clock. As shown in Fig. 4 one terminal of the battery *B* is connected with the clock frame work while the other terminal is connected with the energizing windings *w*. A conductor 52 connects the other terminal of the energizing winding with the contact wire 53 connected with the contact 49 and supported on the contact lever but insulated therefrom by insulation 54. The contact wheel 46 is in contact with the clock framework so that whenever the contact 49 is in engagement with one of the contact wheel teeth 51 the circuit will be closed through the electro-magnet energizing windings and the armature will be swung downwardly. As before stated attraction of the armature causes one winding impulse and restoration

of the armature by the spring 45 causing another winding impulse.

A weighted lever 55 extending from the contact lever tends to swing said lever to hold its contact in the path of the contact wheel teeth. Adjacent the free end of the armature a kick-off lever 56 is pivoted intermediate its end in the lugs 57 extending from the base 10. The inner end of the lever extends below and in the path of the armature while the upstanding outer end 58 of the lever is adjacent the arm 59 extending downwardly from the arbor 48 which supports the contact lever. Figs. 2 and 3 clearly show the operation of the kick-off lever. When the armature is swung suddenly downwardly upon energization of the electro-magnet core, the lever end 58 will strike the arm 59 and the contact lever will be suddenly swung outwardly away from the contact wheel to disengage its contact from the contact wheel teeth. Above the contact wheel a latch lever 60 is pivoted at its inner end on the rear frame plate 12, this lever at its outer end having the outer abutment step 61 and the inner abutment step 62. When the electro-magnet is energized the kick-off lever will strike the arm 59 sufficiently to cause the contact lever to be thrown outwardly far enough to be caught by the outer abutment step 61, and to withdraw the contact lever contact from the path of the contact teeth, as clearly shown in Fig. 5. This latch lever is raised at the proper time to permit the contact lever to swing inwardly sufficiently to engage with the abutment step 62, in which position it is in the path of the contact teeth on the contact wheel as shown in Fig. 6, the upper end of the lever traveling along the abutment step 62 during engagement of the lever contact with a contact tooth.

In the construction shown the contact wheel has four contact teeth *a*, *b*, *c* and *d*, and shortly after the contact lever has been swung back by the kick-off lever and has been caught by the latch 60, the next contact tooth will pass under and in engagement with the projection 63 on the latch and the latch will be raised to permit the contact lever to swing into engagement with the inner step 62 to present its contact 49 in the path of this next contact tooth. It will be noted that the projection 63 presents a sharp scraping edge so that engagement of a contact tooth with the latch causes the tooth to be scraped clean, and just before a tooth engages with contact 49 it will wipe across the edge of projection 64 on the contact lever in advance of the contact. Each tooth is thus twice cleaned before it engages with the contact 49 to close the electro-magnet circuit. Engagement of a tooth with the projections 63 and 64 also cleans and brightens these projections so that they will

be cleaned before they engage with and clean off the next contact tooth. For cleaning the contact face of the contact 49, wiper projections *e*, *f*, *g* and *h* are provided on the 5 wheel 65 which is adjacent the contact wheel 46 and is secured to travel therewith but is insulated therefrom. As shown in Fig. 1 the wiper projections extend transversely over the contact wheel 46 so as to engage 10 with the projections 63 and 64 and with the contact 49. As shown in Fig. 4 the wiper projections are also inclined so as to present a scraping edge. The main purpose of the wiper projections is to wipe across and 15 thoroughly scrape clean the contact face of the contact 49, but before they reach the contact they co-operate with the latch lever projection 63 and the projection 64 for reciprocal cleaning. In Figs. 5 to 8 the cycle 20 of the cleaning operation is clearly illustrated. In Fig. 5 the contact arm has just been thrown back by the kick-off mechanism, the arm being locked by the outer step 61 of the latch lever 60, the contact 49 being 25 separated from the contact teeth *a*. The contact and wiper wheels rotate in the direction of the indicating arrow and as shown in Fig. 6 the wiper *b* comes into engagement 30 with the latch lever and raises it sufficiently to permit the contact lever to swing from the step 61 to the inner step 62 in order to hold its contact 49 in the path of the wiper projection *e*, this projection having had engagement with the latch lever projection to 35 clean this projection and to itself be cleaned. The wiper *e* then travels across the projection 64 on the contact lever and reciprocal cleaning of the engaging surfaces takes place here, the wiper being then thoroughly 40 cleaned before it reaches the contact 49. As its edge wipes across the contact the contact is thoroughly cleaned and brightened so that when the contact tooth *b* has wiped across and been further cleaned by the projection 45 64, electrical engagement of the tooth with the contact 49 will be clean and efficient. In Fig. 8 the wiper *e* has just cleaned the contact 49 and the tooth *b* is just ready to engage with the projection 64 and then the 50 contact 49, the next wiper *f* being in cleaning engagement with the latch lever projection 63. During engagement of a contact tooth or wiper projection with the latch lever, the lever is raised a trifle in order that 55 its weight may bear against the tooth or projection. However the raising is not sufficient to permit the contact arm 47 to leave the inner step 62. Engagement of a contact tooth or wiper projection with the projection 64 or the contact 49 will swing the contact lever outwardly a trifle so as to permit the weight lever 55 to exert pressure between the engaging surfaces, but such outward swing is not sufficient to permit the 60 contact arm to leave the step 62. The ad- justment is such that when the electro-magnet is energized and the kick-off mechanism actuated the latch lever projection 63 will be between a contact tooth and the adjacent wiper projection, the lever being then free 70 to drop to bring its outer step 61 into detent engagement with the swung out contact arm, this arrangement being shown in Fig. 5. Outward swing of the contact lever is limited by the stop 66 (Fig. 2). Thus each 75 contact is subjected to a thorough scraping, cleaning and brightening before it engages with another contact to close the electrical circuit, and the scraping and cleaning members are themselves subjected to a cleaning 80 process before they engage with the contacts to clean them. The friction is thus reduced to a minimum and the circuit quickly closed and immediately reopened by the kick-off mechanism. The contact making engagement therefore does not exert any appreciable drag on the clock train and very little current is therefore consumed during a contact making engagement. This clean, friction-less contact also makes it possible to use 85 a lighter main spring than would ordinarily be necessary for driving the clock work. By means of a light, small and finely tempered steel main spring I am enabled to powerfully and efficiently drive the clock 90 movement, the incremental winding of the spring by the electro-magnet mechanism always keeping the spring sufficiently wound to operate the most efficiently. However in my arrangement there can be no over-wind- 100 ing or straining of the main spring. The adjustment is such that the winding will tend to be just a trifle ahead of the unwind- ing. However, if when the electro-magnet is energized, the main spring is close to be- 105 ing fully wound then it will resist sufficient movement of the armature to operate the pawl and ratchet winding-up mechanism, but such winding-up will be delayed until the spring has become unwound sufficiently 110 to permit complete attraction of the armature. If after attraction movement of the armature the spring is fully wound or close to it, then it will resist the spring 45 suf- 115 ficiently to prevent operation of the push pawl ratchet mechanism until the main spring has become unwound a sufficient dis- tance. Thus the main spring is fully pro- 120 tected against undue strain while at the same time it is kept sufficiently wound up to efficiently and powerfully operate the clock train.

A bracket 66' secured to the base 10 over- 125 hangs the armature a distance to limit its upward movement by the spring 45. To deaden the noise of impact this bracket is faced with a piece 67 of leather, rubber or other noise absorbing material. To prevent contact of the armature with the pole ends, 130 a cushion 68 of leather or other suitable ma-

terial is secured on the base 10 below the armature. By preventing engagement of the armature with the pole ends, sticking of the armature to such ends will be prevented. The cushion also assists the facing 67 in making the operation of the armature noiseless.

A plate 69 secured to the electro-magnet frame carries the various terminal posts 70, 71 and 72. The posts 70 and 72 are insulated from the plate 69 and connect with the terminals of the energizing winding of the electro-magnet, while the post 71 is in electrical contact with the plate 69 and thus with the metallic frame work of the clock. During operation of the clock the electric current source terminals are connected with the posts 71 and 72. When the electric circuit is withdrawn from the clock the main spring will of course run down, and then to wind the clock ready for operation the electric current source terminals are first applied to the terminal posts 70 and 72 to cause a few impulses of the electro-magnet and sufficient winding up of the main spring so that the clock will then continue to operate when the terminals are secured to the posts 71 and 72.

During the flow of energizing current to the electro-magnet the generated counter-electro motive force will tend to set up a current in the opposite direction which current would tend to cause parting at the contacts unless another outlet were provided therefor. I therefore connect a non-inductive resistance R between the terminals of the energizing windings through which the generated counter-current can be taken up when the electro-magnet circuit is broken. The non-inductive resistance is shown in the form of a coil secured to the plate 69.

As changes and modifications may be made without departing from the scope of my invention, I do not desire to be limited to the exact construction, arrangement and operation shown and described.

I claim as follows:

1. In an electrical circuit, contacts for closing said circuit, and means for scraping said contacts clean before they engage to close the circuit.

2. In an electrical circuit, contacts for controlling said circuit, and scrapers for traveling over said contacts to clean them before they engage to close the circuit.

3. In combination, a stationary electrical circuit contact, a traveling contact for engaging with the stationary contact to close the circuit, a traveling cleaning member adapted to scape across the stationary contact to clean it, and a scraping member in the path of the traveling contact to clean such contact, cleaning being accomplished before said contacts engage to close the circuit.

4. The combination with an electrical cir-

cuit, of a stationary controlling contact, a rotating structure, contacts on said rotating structure for engaging successively with said stationary contact to close said circuit, means in the path of said traveling member contact for cleaning its contacts, and scraping edges on said rotating structure for engaging with said stationary contact to clean it, cleaning being accomplished before said contacts engage to close the circuit.

5. In an electrically controlled clock, the combination of a clock train, a main spring for driving said train, an electro-magnet for winding said spring, an electrical circuit for said electro-magnet, a stationary contact forming one terminal of said circuit, a contact wheel driven by the clock work and having contact teeth thereon for successively engaging with said stationary contact, said wheel forming the other terminal of said circuit, a disc connected with the clock work adjacent said contact wheel but insulated from the electrical circuit, a plurality of cleaning projections on said disc extending over said contact wheel in advance of the contact teeth thereon, said cleaning projections engaging with said stationary contact to clean such contact in advance of the contact teeth, and a cleaning member in the path of said teeth having cleaning projections for cleaning the teeth prior to their engagement with said stationary contact.

6. In an electrically controlled clock, the combination of a clock train, a driving spring therefor, an electro-magnet for controlling the winding of said spring, a contact wheel rotated by the clock train and having a plurality of contact teeth thereon, a hinged arm having a contact for co-operating with said teeth to control the electrical circuit for said electro-magnet, means tending to swing and hold said arm in position with its contact in the path of said teeth, means controlled by the electro-magnet for swinging said arm outwardly to break said circuit immediately after closure thereof, a latch adapted to lock said arm in outwardly swung position, cleaning projections carried with said contact wheel for engaging with said contact arm contact to clean said contact before engagement thereby of the contact teeth, and a cleaning projection on said latch in the path of said teeth and associated cleaning projections whereby said contact teeth and cleaning projections are cleaned prior to their engagement with said arm contact and whereby said latch is raised to release the arm to restore its contact in the path of said teeth.

7. In an electrically controlled clock, the combination of a clock train, a driving spring therefor, an electro-magnet for controlling the winding of said spring, a contact wheel rotatable with the clock train and having a plurality of contact teeth thereon,

- a contact arm adapted to swing toward and away from said contact wheel and having a contact point for co-operating with said contact teeth to close the circuit for said electro-magnet, a cleaning projection on said arm in advance of said contact point for engaging with said teeth to clean them before they engage said contact point, and cleaning projections traveling with said contact wheel to engage with said arm projection and contact point thereon to be first cleaned by said projection and then to clean said contact point in advance of contact engagement with said point by said contact teeth.
8. In an electrically controlled clock, the combination of a clock train, a driving spring therefor, electro-magnet mechanism for controlling the winding of said spring, a contact wheel driven with said train and having a plurality of contact teeth, said wheel forming one terminal of the electro-magnet circuit, an arm adapted to swing toward and away from said contact wheel and having a contact point for co-operating with said contact teeth to close the electro-magnet circuit, means tending normally to hold said arm with its contact point in the path of said contact teeth, a finger extending from said arm, a kick-off lever pivoted intermediate its ends, one end of said kick-off lever being in the path of the electro-magnet armature and the other end of said kick-off lever being adjacent said finger, attraction of said armature causing said kick-off lever to engage with said finger and swing said arm to carry its contact point out of the path of said contact teeth, and a latch for engaging with said arm to hold it in swung position.
9. In an electrically controlled clock, the combination of a clock train, a driving spring therefor, an electro-magnet for controlling the winding of said spring, a contact wheel driven with said train and having a plurality of contact teeth, said wheel forming one terminal of said electro-magnet circuit, a contact arm having a contact point for co-operating with said teeth to close the electro-magnet circuit, means tending to swing and hold said arm in position to hold its contact point in the path of said teeth, a finger extending from said arm, a kick-off lever pivoted near one end, the short end of said lever being in the path of the armature when attracted, the long end of said lever terminating near said finger whereby when said armature is attracted said lever will engage with the finger to swing said contact arm away from said contact wheel teeth, and a latch for locking said contact arm in swung position, said contact teeth engaging with said latch lever during their travel to raise said latch lever to permit said arm to carry its contact point back into the path of said contact teeth.

In witness whereof, I hereunto subscribe my name this 15th day of September, A. D. 1919.

ALFRED L. SOHM.
